UNITED STATES PATENT OFFICE.

LYMAN DAGGETT, OF BOSTON, MASSACHUSETTS.

IMPROVED INNER SOLE.

Specification forming part of Letters Patent No. **55,247**, dated June 5, 1866.

To all whom it may concern:

Be it known that I, LYMAN DAGGETT, of Boston, in the county of Suffolk and State of Massachusetts, have invented a new and useful or Improved Inner Sole for Boots or Shoes; and I do hereby declare the same to be fully described in the following specification and represented in the accompanying drawings, of which—

Figure 1 is top view, Fig. 2 a bottom view, and Fig. 3 a transverse section, of it.

It is composed of a sheet of india-rubber, A, or other suitable equivalent, and a lining or covering, B, of cloth or leather. It is punctured with numerous holes, *a a*, going through it at regular distances apart. I prefer to arrange them as represented in Fig. 1. The lower surface of the sheet of rubber is to be made with projections, as shown at *b b*, and with cavities or passages *c* extending between or between and around the projections, and communicating with the holes *a*, which go down through the sole and between the said projections. These projections serve, while the sole is in use, to support it on the inner sole of the shoe or boot. The passages or cavities allow air to freely circulate underneath the false sole and

up through the various holes in it. The false sole is thus elastic and flexible. It insulates the foot of the wearer from the sole of the shoe, so as to keep the foot dry in case the sole become wet. By allowing air to circulate under and through the sole, perspiration of the foot can go on freely without injury to the foot or damping the stocking. Besides this, the sole constitutes an elastic body, which is soft or yielding to the foot and serves to relieve it or its joints from the effect of concussions of the shoe while the wearer may be either walking or running on pavements or a hard ground or surface.

If desirable, the sole may be fixed in so as to form part of a boot or shoe.

I claim as my invention—

The flexible inside water-proof elastic sole, as made with the supporting projections extending from its lower surface, and with passages around and between such, and holes leading therefrom up through the sole, the whole being substantially as described.

LYMAN DAGGETT.
